UNITED STATES PATENT OFFICE.

JOHN C. COURTNEY, OF STREATOR, ILLINOIS, ASSIGNOR OF ONE-HALF TO
FAWCETT PLUMB, OF SAME PLACE.

CORN-PLANTER.

SPECIFICATION forming part of Letters Patent No. 611,356, dated September 27, 1898.

Application filed June 15, 1897. Serial No. 640,892. (No model.)

To all whom it may concern:

Be it known that I, JOHN C. COURTNEY, a resident of Streator, in the county of La Salle and State of Illinois, have invented certain new and useful Improvements in Corn-Planters; and I do hereby declare the following to be a full, clear, and exact description of the invention, such as will enable others skilled in the art to which it appertains to make and use the same.

My invention relates to an improvement in corn-planters, and more particularly to check-row planters, one object of the invention being to so construct the machine that the main frame shall be composed of a single piece of metal and so that said frame shall be balanced on the axle.

A further object is to provide a simple, continuous, and positive check-rower.

A further object is to provide simple and efficient means for supporting and operating the shaft which transmits motion to the perforated dropping-disk.

A further object is to provide a check-row corn-planter with efficient means for causing the machine to operate as a drill.

A further object is to so construct the seed-box as to keep the weight of the grain (corn) from unduly pressing on the dropping-plate when said box is full of corn.

A further object is to produce a corn-planter which shall be comparatively simple in construction, accurate in operation, and effectual in all respects in the performance of its functions.

A further object is to so construct a corn-planter that the leg or boot through which the corn passes can be disposed under the axle, or nearly so, and to provide suitable devices (connected with the leg or boot) for covering the planted corn.

A further object is to so construct a corn-planter that the leg or boot can be located under or nearly under the axle and at the same time be permitted to be adjusted vertically with respect to the ground.

A further object is to construct the frame of a corn-planter so as to avoid the jointed arrangements heretofore employed between the part of the frame which supports the

dropping mechanism and the wheels and to provide a rigid frame, a fixed tongue connection, and a seat so placed that the weight of the driver will balance the tongue.

With these objects in view the invention consists in certain novel features of construction and combinations and arrangements of parts, as hereinafter set forth, and pointed out in the claims.

In the accompanying drawings, Figure 1 is a plan view of a machine embodying my improvements. Fig. 2 is a side elevation. Fig. 3 is an elevation with parts removed. Figs. 4, 5, 6, and 7 are detail views of portions of the dropping or feeding mechanism. Fig. 8 is a detail view of devices for operating the drill mechanism. Figs. 9 and 10 are detail views showing the arrangement of the covering devices. Figs. 11, 12, 13, 14, and 15 are detail views illustrating the check-rower devices. Fig. 16 is a detail view showing the arrangement of valves in the legs of the machine.

A represents the main frame of the machine and is made of a single piece of angle-iron and preferably of a general rectangular form, comprising side bars *a*, an end or cross bar *b*, and forwardly-projecting converging bars *c*, the latter terminating in parallel arms *d*, which are secured to the tongue *B* of the machine. The tongue *B* projects some distance within the main frame *A* and is secured to the axle *C* of the machine. Bars *f*, of angle-iron, are disposed parallel with the side bars *a* of the frame a short distance inwardly therefrom and are securely bolted at their ends to the rear cross-bar *b* and the front bars *c*. To the under side of the bars *f* and the side bars *a* at points in rear of the center of frame *A* the axle *C* is secured, said axle projecting a suitable distance beyond the frame to accommodate the carrying-wheels *C'*.

A driver's seat *E* is located over the rear end of the frame and supported by standards *g* *h*, the bar *g* being secured at its lower end to the axle *C* and the standards *h* being bolted at their lower ends to the rear cross-bar *b* of the frame.

The legs *F* of the machine by means of which the corn is conducted to the furrow are

- located in close proximity to the axle slightly in advance of the same and between the carrying-wheels C', the lower ends of said legs terminating normally almost directly under 5 the axle. Each leg comprises a body portion 1, which constitutes the seed-tube, and a furrow-opener 2, having an upwardly-projecting portion 3, which telescopes over the body portion 1. The upper end of the body portion 10 of each leg F terminates between the bars a of the frame at the respective sides thereof and are provided with lateral flanges 4, which lie upon and are bolted to said bars. These flanges serve (in part) to support the 15 seed-hopper 5 and the feeding mechanism located under the same. The hoppers and feed mechanism are further supported by arms 7, projecting forwardly from the legs.
- The feed mechanism employed will prefer- 20 ably be that for which Letters Patent were granted to me February 19, 1895, and des- 25 ignated by No. 534,361. In order to pre- 30 vent the weight of the corn in the hopper from unduly pressing upon the perforated plate of the feeding mechanism, especially 35 when said hopper is full, and thus affecting the accurate operation of said mechanism, I provide the hopper a short distance above its lower end with a false bottom i, which is dish- 40 shaped or inclined toward its center, where it is provided with an opening j, through which the corn will gradually flow. In this manner the weight of the main body of grain within 45 the hopper will be kept off of the feeding mechanism and a shallow and uniform depth of corn will be maintained in the chamber k under the false bottom and on the feed mechanism, and consequently insuring a uniformity of pressure on the feed mechanism and the 50 free and accurate operation of the latter.
- Each leg is provided at a point between its ends with an arm 8, preferably curved downwardly at its free end. Each furrow-opener is made with an extension 8', which projects 55 forwardly and upwardly and at its extremity is pivotally connected to the free end of arm 8. The furrow-opener 2 (lower part of the leg F) can thus be swung in the arc of a circle on its pivotal connection with the arm 50 8 and made to move more or less over the body portion 1 of the leg, thus permitting the furrow-opener to be adjusted for the desired depth of furrow or to be raised entirely out of the ground. Each arm 8 and the portion 55 1, from which it projects, is braced by means of a rod or brace 9, attached at one end to said arm 8 and secured at the other end to a transverse bar 10 of the frame, and each furrow-opener is braced by means of a bar 11.
- Curved brackets 11^a are secured to the telescopic section (furrow-opener) 3 of each leg F and project rearwardly therefrom. Between the free ends of the brackets 11^a one end of an arm 12 is attached, and from the 60 free end of said arm inclined pintles 13 project laterally. On these pintles covering-disks 14 are mounted so as to be closest together

where they engage the ground. The ends of each pintle or axle 13 are connected with the lower telescopic section of the leg by means 70 of adjustable bars 15, one end of each of which is made with an elongated slot 16 to receive a lug 17, projecting from said telescopic sections 1 to 3. By arranging the covering-disks as above described the soil will be 75 properly thrown over the seed without running over the planted row, thus avoiding undue packing of wet soil, and the corn will be covered with loose earth, which is a decidedly better way of covering it. By attaching the 80 covering-disks in the manner above explained they can be readily adjusted to cover the grain to any desired depth.

A shaft 18, having crank-arms 19 at its re- 85 spective ends, is mounted in brackets 20, de- pending from the framework, and said crank-arms are connected with the lower telescopic section 3 of the leg by means of links 21. A lever 22 is secured to the crank-shaft 18 and provided with a locking-bar 23, adapted to 90 engage a notched segment 24, secured to the framework. By means of the lever 22 the furrow-openers 2 can be raised or lowered to adjust them to any desired depth of furrow or to raise them entirely out of the ground, as 95 shown in Fig. 3. The covering-disks being carried by the furrow-openers 2, they will be raised or lowered therewith when the lever 22 is operated.

The arms 7, which project from the upper 100 sections of the legs F, are made with bearings 25 for the accommodation of a shaft 26, having a beveled gear 27 at its ends for transmitting motion to the feeding mechanism. The operating-shaft 26 is further supported by 105 bearing-blocks 28, secured to the side bars of the frame A.

The feed mechanism can be operated inter- 110 mittently when the machine is to be used as a check-row planter by imparting an inter- 115 mitting or step-by-step motion to the operating-shaft 26, or said feed mechanism can be operated continuously when the machine is to be employed as a drill by imparting a continuous motion to said operating-shaft. I 120 will first explain in detail the construction and operation of the check-row devices and then explain the mechanism whereby the feed mechanism can be given a continuous operation for the purpose of drilling.

The transverse bar 10 of the framework is provided with lateral extensions 29, to the end of each of which one end of a bar 30 is se- 125 cured. The other ends of the bars 30, after having been bent at right angles, are secured to the respective ends of the axle C, said bars 30 and the projecting ends 29 of the trans- 130 verse bar 10 thus constituting lateral frames or brackets, which are utilized for supporting the check-row mechanism G, and these being identical in construction a detail description of one will suffice for both. The base-plate 31 of the check-rower is secured to the bar 30 of the lateral bracket, and from

said plate 31 arms 32 project outwardly. The arms 32 are provided at their outer ends with perforated lugs 33, and similar perforated lugs 34 project from sheave-plates 35, the latter being connected together by an integral web or brace 36. A rod 37 passes through the perforated lugs 33 34, and thus hinges the sheave-plates to the arms 32. Sheaves 38 are mounted on pintles projecting from the plates 35, and the latter are maintained normally in their working position by means of a latch 39, attached to one of the arms 32 and adapted to engage a lug 40, projecting from one of the sheave-plates, said latch being provided with an arm 41, to which a suitable device can be attached, whereby the driver will be enabled to withdraw the latch and thus permit the sheave-plate and parts attached thereto to swing out of engagement with the knotted check-row wire 42.

Projecting upwardly from sheave-plates on each side of the sheaves are vertical guides 43, which hold the wire 42 in contact with the sheaves.

25 A segmental block 44 is secured to the base-plate 31 of the check-rower and to said block. The check-rower lever 45 is pivoted and limited in its movements by means of stops 46, projecting from said block. The lever 45 is 30 provided with fingers 47, between which the check-wire 42 passes, and the ends of said fingers are curved or recessed, as at 48, and adapted to engage the knots of the check-wire. During the forward movement of the 35 machine the knots or buttons on the check-row wire 42 will engage the curved or recessed ends of the fingers 47 at the extremity of the check-rower lever 45 and move said lever back at an angle until the knots are released 40 from the curved or recessed ends of the fingers 47, the check-wire being held in place between said fingers during the movement of the lever 45 by the intermediate arched web or brace 36. During this backward movement 45 of the lever 45 motion will be imparted to the operating-shaft through the medium to the operating-shaft through the medium of devices which will now be explained.

A series of bearing or journal boxes 48^a project inwardly from the transverse bar 10 50 of the framework and the lateral extensions 29 of said bar for the reception of a transverse shaft 49, having crank-arms 50 at its respective ends, and with these crank-arms the check-rower levers 45 are connected by 55 means of pitmen 51. The shaft 49 is also provided between its ends with a crank-arm 52, with which one end of a spring 53, Fig. 3, is attached, the other end of said spring being attached to the tongue B or to the frame of 60 the machine, said spring serving to return the check-rower lever 45 to its normal position after it has been moved backwardly, as above explained.

A bracket 54 is secured to one of the side bars *a* of the main frame, and to the arms of this bracket guides 55 are secured for the accommodation of a sliding bar 56, to which

latter motion is imparted by means of a pitman 57, attached, respectively, to one end of said sliding bar and a crank-arm 58 on the 70 shaft 49. A ratchet-wheel 59 is secured to operating-shaft 26 at a point between the arms of the bracket 54 and immediately under the sliding bar 56. A curved dog 60 is pivoted to the sliding bar 56 and adapted to engage the teeth of the ratchet-wheel, so as to turn the operating-shaft when motion is imparted in one direction to said sliding bar and cause the operation of the feeding mechanism to discharge a few grains of corn, this 80 sliding movement of the bar 56 being accomplished by the backward movement of the check-rower lever 45 when the latter engages a button or knot of the check-row wire 42. Retrograde movement of the ratchet-wheel 85 and the operating-shaft to which it is attached will be prevented by the engagement of a dog 61 (pivoted to the bracket 54) with lugs 62 on the back of said ratchet-wheel. A plate 63, having a beveled arm 64, is secured to the 90 sliding bar 56, so that when the latter is moved forward to operate the operating-shaft 26 said beveled arm will engage one of the lugs 62 and thus prevent the operating-shaft from being turned too far.

When the grain leaves the feeding mechanism under the hoppers, it falls on valve 65 at the upper ends of the body portions 1 of the legs F, and when these valves are opened the grain falls onto valves 66 at the lower 100 ends of said body portions 1 of the legs, from which latter valves the grain is discharged into the furrow. These valves are operated simultaneously in reverse directions, so that when the upper ones are opened the lower 105 ones are closed, and vice versa. To accomplish this, a shaft 67 is mounted in lugs 68, projecting from the upper ends of the portions 1 of the legs F and provided with bell-crank levers 69, the arm 70 of each bell-crank 110 lever being attached to one of the upper valves 65 and the arm 71 being connected, through the medium of a rod 72, with an arm 73 on the shaft or support of the lower valve 66.

The shaft 67, which extends transversely 115 across the machine, is provided at a point between its ends with a crank-arm 74, and this crank-arm is connected by means of a rod 75 with a crank-arm 76 on the transverse shaft 49.

From this construction and arrangement of parts above described it will be seen that when the check-rower levers 45 are moved backwardly by engagement with the knots of the wire 42 motion will be transmitted simultaneously to the operating-shaft 26 and the valve-shaft 67, resulting in the discharge of grain from the hoppers onto the upper valves 65 of the legs, at the same time discharging grain from the valves 65 through a portion 1 125 of the leg and onto the lower valve 66 and from the latter to the furrow. Thus it will be seen that while a few grains are being discharged from the valve 66 into the furrow

other grain will be on their way through the leg to take the place on the valve 66 (when the latter again closes) of the grains which had been planted. The valves 65 66 immediately close after discharging the grain, and as soon as the upper valve 65 has discharged its corn a new supply of a few grains will be discharged onto it from the hopper by the feeding mechanism.

10 I will now explain the construction and arrangement of the devices whereby the machine can be operated as a drill.

A plate 77 is secured to the bars *a f* at one side of the frame A in rear of the axle, and 15 this plate is provided with arms 78, having bearings for a shaft 79. The shaft 79 is made in two parts connected together by means of a clutch 80, the parts of which are held together by means of a spring 81. The clutch 20 is adapted to be operated by a pivoted lever 82, and the parts of the clutch will be maintained out of engagement with each other while the machine is operating as a check-rower by the engagement of a locking-bar on 25 said lever with a notched segment 83. One section of the shaft 79 is provided with a gear-wheel 84, which receives motion from a gear-wheel 85 on the hub of one of the carrying-wheels C'. The other section of the shaft 79 30 is provided with a cone of gears 86, from which motion can be imparted by a chain 87 to a gear-wheel 88 on the operating-shaft 26. The gear-wheel 88 is adapted to transmit motion to the dropping-shaft 26 and to have a 35 sliding movement thereon, so that it can be adjusted relatively to the gears of the cone 86 when it is desired to change the speed of the dropping-shaft. From this construction and arrangement of parts it will be seen that 40 a continuous uninterrupted motion can be imparted to the feeding mechanism whereby the machine can be made to operate as a drill.

When the drill mechanism is in operation 45 and the machine is given a backward movement, the parts of the clutch 80 would be thrown out of mesh and no motion would be imparted to the feeding mechanism.

It will be observed that the planting devices of my improved corn-planting machine 50 are located between the wheels and at or near the axle. To do this and yet permit the furrow-opener or shoe to be adjusted for various depths of furrow and for raising it entirely 55 out of the ground, I have constructed said shoe or furrow-opener to telescope over the seed-tubes, thus producing a telescopic leg. This arrangement enables me to dispose of the jointed arrangement of framework here- 60 tofore employed between the part of the planter supporting the dropping mechanism and the wheels, and in place of such jointed frame I employ a rigid frame and a solid tongue connection and place the seat for the 65 driver in such position that the weight of the driver will balance the tongue. With such arrangement the draft of the machine is

light. It will also be observed that my improved check-rower is so arranged that the button or knot on the wire operates at the extreme end of the check-rower lever, but is held in place until the time for its release, when the immediate discharge of the button or knot from the end of the lever will be permitted.

My improvements are in all respects effectual in the performance of their functions.

Various slight changes in the details of construction might be made without departing from the spirit thereof or limiting its scope, and hence I do not wish to limit myself to the precise details herein set forth.

Having fully described my invention, what I claim as new, and desire to secure by Letters Patent, is—

1. In a corn-planter, the combination with a frame, an axle secured thereto and wheels on the axle, of a tongue secured to the front end of the frame and to the axle, a driver's seat over the rear end of the frame and standards secured to said seat, the rear of the frame and the axle, substantially as set forth.

2. A planting-leg consisting of telescoping sections, one section being hinged whereby it swings in the arc of a circle when it moves.

3. A planting-leg consisting of a rigid seed-tube and a furrow-opener or shoe telescoping over said seed-tube, and a pivotal connection between said seed-tube and furrow-opener or shoe, substantially as set forth.

4. A planting-leg consisting of a fixed seed-tube, an arm projecting forwardly therefrom, a furrow-opener or shoe adapted to telescope over said seed-tube, and an extension on said furrow-opener or shoe pivotally connected to said forwardly-projecting arm, substantially as set forth.

5. In a planter, the combination with a frame, of a planting-leg consisting of a rigid seed-tube, a shoe telescoping over the lower end thereof, a forwardly-projecting arm on the seed-tube pivoted to an extension of the shoe, and a brace extending from the free end of said arm and the frame, substantially as set forth.

6. In a corn-planter, the combination with a frame, of a planting-leg consisting of a rigid section and a telescoping section, a rock-shaft mounted on the frame and having a crank-arm, a connection between said crank-arm and the telescopic section of the leg, an operating-lever secured to said rock-shaft and a locking device for said operating-lever, substantially as set forth.

7. In a corn-planter, the combination with a planting-leg comprising a rigid and a telescopic section, of brackets secured to the telescopic section, an arm pivoted between said brackets, pintles at the free end of said arm, covering-disks on said pintles, and slotted bars connecting said pintle with the telescopic section, substantially as set forth.

8. In a corn-planter, the combination with a planting-leg comprising a rigid and a tele-

scopic section, of an arm adjustably connected with the telescopic section and having inclined pintles, and inclined covering-disks mounted on said pintles, substantially as set forth.

9. In a corn-planter, the combination with a frame, feed mechanism, and a shaft adapted to transmit motion to said feed mechanism of a check-rower lever, a ratchet-wheel on said shaft, a sliding bar, a dog on said sliding bar adapted to engage the ratchet-wheel, and connections between said sliding bar and the check-rower lever, substantially as set forth.

10. In a corn-planter, the combination with a frame, feed mechanism, a shaft adapted to transmit motion to the feed mechanism and a pivoted check-rower lever, of a ratchet-wheel on said shaft, a sliding bar, connections between said sliding bar and said check-rower lever, a dog pivoted to the sliding bar for transmitting motion to the ratchet-wheel, and another dog pivoted to the frame and adapted to prevent retrograde movement of the ratchet-wheel and shaft, substantially as set forth.

11. In a corn-planter, the combination with a frame, feed mechanism, a shaft to transmit motion to the feed mechanism, and a check-rower lever, of a ratchet-wheel on the shaft, a sliding bar, a dog attached to the sliding bar and adapted to propel the ratchet-wheel, and a plate or arm on the sliding bar adapted to engage the ratchet-wheel and prevent it from being turned too far, substantially as set forth.

12. In a corn-planter, the combination with a frame, feed mechanism, a shaft for transmitting motion to said feed mechanism, and a check-rower lever, of a ratchet-wheel on said shaft and having peripheral teeth on one face, a sliding bar, connections between said sliding bar and the check-rower lever, a dog attached to the sliding bar and adapted to engage the peripheral teeth of the ratchet-wheel, to propel it, a dog pivoted to the frame and adapted to engage the side teeth of the ratchet-wheel to prevent retrograde movement thereof, and a plate or arm secured to the sliding bar and adapted to engage said side teeth of the ratchet-wheel to prevent

the same from being turned too far, substantially as set forth.

13. In a corn-planter, the combination with a frame, feed mechanism, a shaft to transmit motion to the feed mechanism, and a pivoted check-rower lever, of a ratchet-wheel on said shaft, a sliding bar, a dog pivoted to the sliding bar and engaging the ratchet-wheel, a crank-shaft mounted on the frame, a pitman between the crank-shaft and the sliding bar, and a pitman between the crank-shaft and the check-rower lever, substantially as set forth.

14. The combination with a frame, an axle, wheels on the axle, grain-feeding mechanism, and a feed-shaft, of a counter-shaft made in sections, a clutch between said sections, gearing between one section of the shaft and one of the wheels, a cone of gears on the other section of the counter-shaft, an adjustable gear on the feed-shaft and a chain passing over said adjustable gear and one of the gears of the cone, substantially as set forth.

15. In a planter, the combination with a frame, an axle, wheels on the axle, a seed-hopper, feed mechanism and a feed-shaft, of a plate secured to the frame and having arms provided with bearings, a two-part counter-shaft mounted in said bearings, a clutch between the sections of the counter-shaft and adapted to yield when retrograde motion is transmitted to one section of the shaft, a spring bearing against one section of the clutch, a lever attached to said clutch, gearing between one section of the counter-shaft and one of the wheels, and gearing between the other section of the counter-shaft and the feed-shaft, substantially as set forth.

16. In a planter, the combination with a hopper and feeding mechanism under the same, of a concave false bottom having a hole in its center, in said hopper above the feed mechanism, substantially as set forth.

In testimony whereof I have signed this specification in the presence of two subscribing witnesses.

JOHN C. COURTNEY.
